(57) **CLAIM**

The ornamental design for a jewelry component, as shown and described.

DESCRIPTION

FIG. 1 is a front perspective view showing my new design; FIG. 2 is a top plan view thereof;

FIG. 3 is a right side elevational view thereof (the left side elevational view being identical thereto); and,

FIG. 4 is a bottom plan view thereof.

The broken lines shown in the drawings represent unclaimed portions of the jewelry component and form no part of the claimed design.
